BRIDGE MOUNTABLE STRINGED INSTRUMENT BOW GUIDE

Richard O. Gordon, 91 S. Jane Ann Way,
Campbell, Calif. 95008

Filed May 23, 1974, Ser. No. 472,639

Term of patent 14 years

Int. Cl. D17—03
U.S. Cl. D56—1 A

Fig. 2.

Fig. 1.

FIG. 1 is a perspective view of a bridge mountable stringed instrument bow guide showing my new design;
 FIG. 2 is a rear elevational view;
 FIG. 3 is a top plan view;
 FIG. 4 is a right side elevational view;
 FIG. 5 is a front elevational view;
 FIG. 6 is a bottom plan view; and
 FIG. 7 is a sectional view taken along line 7—7 of FIG. 5.

I claim:

The ornamental design for a bridge mountable stringed instrument bow guide, as shown.
